UNITED STATES PATENT OFFICE.

JOHN FRANKLIN STUCKERT, OF PHILADELPHIA, PENNSYLVANIA.

ROOFING JOINT.

Application filed September 14, 1925. Serial No. 56,134.

To all whom it may concern:

Be it known that I, JOHN F. STUCKERT, a citizen of the United States, residing at Philadelphia, in the county of Philadelphia and State of Pennsylvania, have invented certain new and useful Roofing Joints, of which the following is a specification.

This invention, generally stated, relates to a roofing structure and has more especial relation to roofing joints therefor.

The leading object of the present invention is to provide a roofing structure which is of simple, efficient and comparatively inexpensive structure whereby the roofing joints may be effectively sealed against leakage.

Other and further objects not at this time more particularly pointed out will be hereinafter referred to.

20 The invention consists of the novel construction hereinafter described and finally claimed.

The nature, characteristic features and scope of the invention will be more fully understood from the following description taken in connection with the accompanying drawings forming part hereof, in which:

Fig. 1, is a fragmentary view in longitudinal section illustrating a roofing structure embodying the invention.

Fig. 2, is a view in cross section taken upon the line 2—2 of Fig. 1.

Fig. 3, is a fragmentary view in plan of Fig. 1.

Fig. 4, is a fragmentary view in section illustrating a detail of construction.

Fig. 5, is a similar view illustrating still another form of construction; and

Fig. 6, is a similar view illustrating still another form of construction.

For the purpose of illustrating my invention I have shown in the accompanying drawings several forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, the reference numeral 1 designates so-called

roofing boards which may be of any suitable material. These roofing boards are supported by any suitable structure 2 and may be secured to place by bolts 3, the number of which is immaterial, and which may be arranged at desired points. The joints of the roofing boards are designated by the reference numeral 4 and extend longitudinally of the roof and it is such joints that I desire to effectively close. Covering

each joint 4 above the roofing boards 1 is a strip 5 which extends longitudinally, or in other words, coextensive with the joints 4. Arranged crosswise with respect to strips 5 are other strips 6, best seen in Fig. 3. In

practice the strips 6 are located between the roofing boards 1 and the strips 5. Such strips 5 and 6 are secured with respect to the roofing boards 1 by bolts 3, said bolts being arranged at various intervals as practice may dictate. Extending in parallelism with each strip 5 are pieces of rope, hemp or the like 7, four strands thereof being shown in Fig. 3. These strands of rope or the like are extended around a bolt 3, as

clearly shown in Fig. 3. Around the rope or hemp thus positioned is provided a filling of cementitious composition 8, as clearly shown in Fig. 2. This cementitious material serves to maintain the rope, hemp or the like 7 embedded within the cementitious material to provide an effective and efficient sealing joint. Of course the bolts 3 and nuts complementary thereto serve to provide

rigidity of parts. Some of the bolts 3 may carry inverted channel beams 9, see right hand side of Fig. 1, and also see Fig. 2. Thus the rope, hemp, or the like strands 4 may be also positioned between the roofing boards 1 and the channel beams 9, as shown

in Fig. 2, so that by adding cementitious material between the floor boards and the said channel beam 9 efficient sealing means is provided by the addition of additional tape, rope or hemp. Arranged crosswise of the roofing material 1 are strips of metal 10 which extend beneath the strips 5 and are secured to place as at 11. Arranged beneath each strip 10 and crosswise of the roofing boards 1 are strands of rope, hemp, or the like 12, one end of two strands of said rope terminating short of the side pieces of the strip 5 and all opposite strands of rope or the like being folded as at 13 and extended thereafter below a strip 5 in parallelism

110

with the strands of rope 7, see Fig. 3. In Fig. 2, strands of rope 7 and 15 are provided above and below the roofing boards. Beneath the cementitious material 8 is an inverted channel beam 9 and a gutter 16 is provided below said channel beam.

In Fig. 4, cementitious material and the rope or hemp is shown only above the roofing boards.

10 In Fig. 5, the construction is the same as that shown in Fig. 4, except the channel bar 17 is not inverted as in Fig. 2 but assumes conventional position.

In Fig. 6, a pair of strips 18 are shown, 15 one strip comprising an upper strip and the other strip a lower strip. Between these respective strips rope, hemp or the like 19 is provided and cementitious material 8 is provided as in the foregoing constructions.

20 It will be obvious that any of the constructions shown at the right hand side of Fig. 1 and in Fig. 2, or in Figs. 4, 5, and 6, may be practiced as various roofing structures may require. The main idea, however, is 25 the same in each instance, to wit: covering the joint between meeting roofing boards to prevent the ingress of moisture, rain or snow water and the like.

It will now be apparent that I have devised novel and useful constructions which embody the features of advantage enumerated as desirable in the statement of the invention and the above description and while I have in the present instance shown and 35 described the preferred embodiments thereof which have been found in practice to give satisfactory and reliable results, it is to be understood that the same are susceptible of modification in various particulars without departing from the spirit or scope of the

invention or sacrificing any of its advantages.

Having thus described my invention, what I claim as new and desire to secure by Letters Patent, is:

45 1. A roofing structure comprising in combination, roofing boards arranged side by side with their side and end edges adjacent, a flat strip arranged above each seam between two parallel boards, flat cross strips 50 arranged above meeting end edges of boards, bolts for securing said boards and strips in place, strands of pliable material as rope of circular cross section arranged beneath each strip, said strands being spaced apart 55 and a pair of said strands paralleling each of said strips for at least a part of their extent, and cementitious material in which said rope is embedded.

2. A roofing structure comprising in combination, roofing boards arranged side by side with their side and end edges adjacent, a flat strip arranged above a seam between two parallel boards, flat cross strips 60 arranged above meeting end edges of boards, bolts for securing said boards and strips in place, strands of pliable material as rope of circular cross section arranged beneath each strip, said strands being spaced apart 65 and a pair of said strands paralleling each of said strips for at least a part of their extent, said strands of rope under said cross strips being first doubled over upon themselves and the ends thereof then arranged in 70 parallelism with the rope under the first mentioned strips, and cementitious material in which said rope is embedded.

75 In testimony whereof, I have hereunto signed my name.

JOHN FRANKLIN STUCKERT.
